UNITED STATES PATENT OFFICE

GEORGE A. SCHIPPER, OF AURORA, INDIANA

SANDING MACHINE

Application filed July 25, 1928. Serial No. 295,247.

My invention relates to improvements in machines for sanding round wood turnings such as chair and table legs, spindles, etc.

The principal object of my invention is to provide a sanding machine of simple construction, quiet in operation and requiring a minimum of motive power for the accomplishment of the sanding operations.

A further object of the invention is to provide in a sanding machine means whereby the work may be inserted into and removed from the machine at intervals when the work spindles have stopped, thus eliminating danger to the operator and loss through the breakage of work.

Another object of the invention is to provide in a sanding machine co-acting brushes and work spindles so designed that the work will be equally well sanded throughout, instead of producing an irregular finish by the flexible portions of the brush tending to follow the grooves of the work and thus failing properly to finish the higher surface of the turning.

Further objects of the invention will appear from the following detailed description thereof.

In the drawings:

Figure 1 is a perspective of a machine constructed in accordance with this invention.

Figure 2 is an end elevation of said machine.

Fig. 3 is a detailed front cross-section of the work holder.

Fig. 4 is an end elevation of the specific abrading brush operating mechanism.

Fig. 5 is an end elevation of a single abrading brush.

Fig. 6 is a detailed cross-sectional view of the abrading brush reciprocating mechanism.

The numeral 1 indicates a bed or frame of the machine, said bed being supported on standards 2. Mounted in bearings carried by end brackets 3 and 4 supported on the bed 1 is an oscillating shaft 5. Secured to the oscillating shaft 5 are two arms 6 and 7 carrying bearings 8 and 9 on opposite sides of the shaft 5. The arms 6 and 7 are so spaced on the shaft 5 as to provide room for pulleys 9-a and 10 which are mounted be-

tween said arms on the work spindles 11 and 12. Rotatably mounted on the shaft 5 also between the arms 6 and 7 is an idler pulley 13. Slidably mounted upon the shaft 5 are tail stocks 14 and 15 carrying spindles 16 and 17 in alignment respectively with the work spindles 11 and 12. The tail stocks 14 and 15 are carried by an arm 18 on a collar 19 through which a set screw 20 bears in a groove 21 in the shaft 5. The tail stock spindles 16 and 17 are moved longitudinally in the heads by means of levers 22 against compression springs 23 carried by the heads, said mechanism being of familiar construction and adapted to permit the feeding of the work between the work spindles 11-12 and the tail stock spindles 16-17 respectively.

In a bearing in the end plate of the bed 1 is a shaft 24 to which a main drive pulley 25 is rigidly secured. Inside the bed 1 the shaft 24 is provided with a pulley 26 in the same vertical plane with the pulleys 9-a, 10 and 13. Rotatably mounted on a shaft 27 in the upper portion of the bracket 3 is a pulley 28. An adjustable idler pulley 29 is mounted on a bracket 30 at the rear of the bed 1. The pulleys 28 and 29 are in the same vertical plane as pulley 26. A belt 31 driven by the pulley 26 passes around the pulleys 28 and 29, and is arranged to drive alternately the pulleys 9-a and 10, riding, during the intermediate position of both of said pulleys, upon the pulley 13.

The shaft 5 is oscillated so as alternately to bring the pulleys 9-a and 10 into driven contact with the belt 31 by means of a crank 32 secured on the outer end of shaft 5. The crank 32 is operated by means of a link 33 the lower end of which is pivotally secured at 34 to one point of a star wheel 35. The wheel 35 is driven by rollers 36 carried by a plate 37 rigidly secured on a shaft 38 journaled in cross members 39 between the standards 2, said shaft extending the length of the machine as shown in Figure 1. Adjacent said plate is a locking cam wheel 87 adapted to bear against respective locking sections 86-86 of the star wheel 35, the cut away portion of the cam wheel alternately permitting the star wheel to be rotated a half turn by the

plate 37. The outer end of the shaft 28 is provided with a bevel gear 40 rigidly secured thereto, said gear being in mesh with a bevel pinion 41 securely mounted on a cross shaft 5 42 mounted in bearings 43 carried by the standards 2. The other end of the shaft 42 is provided with a worm wheel 44 driven by a worm 45 carried by a stud shaft 46 mounted in bracket bearings 47 carried by the frame. 10 The outer end of the stud shaft 46 is provided with a pulley 48 rigidly secured thereto, said pulley being driven by a belt 49 from the pulley 50 on the outer end of drive shaft 24. 15 Adjustably mounted on the standards 2 are two high arms 51 the lower ends of said arms being slotted to provide slidable adjustment forwardly and rearwardly on the standards 2, and arranged to be secured on the standards by bolts and nuts 52. The upper ends 20 of the arms 51 support a longitudinal rod 53 on which slidable heads 54 are mounted. Pivotally mounted on the heads 54 are links 55 which in turn carry short links 56 the latter being pivotally secured thereto and pivotally supporting frames 57—57, having bearings 58—58 and 59—59 for shafts 60 and 61. The upper shaft 60 carries a pair of arms 62 and the lower shaft 61 carries a pair of arms 63 between which the brush carrying rods 30 64 are mounted, there being two of such rods carried by the arms of each of the shafts 60 and 61 as clearly shown in Figure 4 of the drawings. The rods 64 are tubular and slotted to provide for securing arcuate shanks 35 65 of the brushes 66 by means of bolts 67, the brushes being also adjustable longitudinally on the rods. The usual slotted sand paper 68 is secured over the brushes by means of clamping members 69 carried by the arms 40 62, and extending along the rods. The pairs of brushes carried by the arms 62 and 63 are adapted to bear alternately on the respective work carried between spindles 11—16 and 12—17 as hereinafter set forth, the arms 62 45 and 63 being oscillated into and out of working position at the proper intervals by means of a crank 70 secured on the upper shaft 60, said crank being operated by a link 71 pivotally secured to a crank 72 carried by a sprocket wheel 73 which is driven by a sprocket chain 74 from a sprocket pinion 75 secured on the shaft 38. The shaft 60 carries a segmental gear 76 which is in mesh with a similar gear 77 secured on the lower shaft 61. 50 It will thus be seen that when the upper shaft 60 is rocked by the crank 70 the lower shaft 61 will be rocked in the opposite direction by the segmental gears. Oscillating motion is given to the frames 57—57 and the brush 55 mechanism carried thereby, in the longitudinal direction of the machine by means of a bar 78 extending downwardly from one of the frames 57, the lower end of said bar being rigidly secured to a horizontal bar 79, see 60 Figures 1 and 6 of the drawings. The other

end of the bar 79 is forked to bear slidably on the shaft 42, and carries a roller 80, adapted to ride upon a cam 81 mounted on the shaft. A tension spring 82 between the bar 78 and the frame holds the roller upon the cam. As will be seen, rotation of the shaft 42 causes oscillation of the bar 79, and hence of the frames 57 and brush mechanisms, the same riding upon the pivotal links 55, etc. 70

In order to stop the respective work spindles when the same are out of operative position in relation to the brushes, a brake strap 83 is provided, one end being secured to the bed 1, and the upper end being secured by tension springs 84 to a rod 85 carried by the 75 bracket 3 on the frame. 80

The operation of the machine is as follows:

In the position shown in Figure 1 the upper operating work spindle 11 and tail spindle 16 are out of operating position, and ready to receive a spindle or other piece of work to be sanded. The operator inserts the spindle between the spindles 11 and 16 by withdrawing the spindle 16 by means of the lever 22 and then releasing the lever to clamp the spindle. The machine being in operation the shaft 5 and spindle mechanisms are rocked intermittently by means of the star wheel 35, link 33 and crank 32, the power being delivered to the star wheel from the drive shaft 24 by means of the belt 49, pulley 48, worm gear 44, shaft 42, bevel gears 41 and 40 and roller carrying plate 37 so as next to bring the pulley 9—a against the belt 31 in which position the spindle to be operated on is in position to contact with the sand brushes. Simultaneously the related brush mechanism is oscillated so as to bear upon the spindle by means of the crank 70, etc., and the other brushes carried away from their related spindle by means of the segmental gears. While the upper spindle is thus being carried into operating position, the lower spindle having completed its work is carried out of operating position, and the pulley 10 is braked 90 against the strap 83 so as to stop its rotation. The sanded spindle is then removed and a new one inserted. While the respective spindles are being operated on they are held positively during the required interval by reason of the locking sections 86—86 of the star wheel bearing positively against the circumference of the cam wheel 87 on the shaft 38; this interval also allowing the operator to remove the completed spindle and to insert a 100 new spindle to be sanded in the idle work spindles. During the entire operation of the machine also, the sand brushes are being oscillated longitudinally on the work by means of the cam 81 and related mechanism. 110

It will be understood, of course, that the timing of the various operations, that is the oscillating of the work spindles and brushes, is such as to permit a spindle to be fully operated upon and completed each half cycle, and 120 130

the brushes are so related with respect to the work by means of adjusting the vertical frames 51 that as the spindle to be operated upon and brushes approach each other the 5 spindle is brought progressively into contact with the brushes. Adjustments may be made for different diameter spindles by adjustment of the standards 51, and also by adjusting the limit of movement of the work 10 spindles by moving the upper end of the link 33 in the slot 88 of the crank 32 which oscillates the spindle.

Having thus fully described my invention, what I claim as new and desire to secure by 15 Letters Patent is:

1. In a sanding machine in combination with a shaft, work spindles mounted on said shaft and carried on opposite sides thereof, means for oscillating said shaft so as to bring 20 said work spindles alternately in operative position and means for rotating each spindle while in such operating position, a frame, a pair of shafts mounted in said frame, each of said shafts being provided with 25 sanding brushes, the brushes on each shaft being arranged to operate upon work carried by one of said work spindles, and means for oscillating said shafts so as to cause the respective brushes successively to contact with the work carried by the respective work spindles when in operative position.

2. In a sanding machine in combination with a shaft, work spindles mounted on said shaft and carried on opposite sides thereof, means for oscillating said shaft so as to bring 35 said work spindles alternately in an operative position and means for rotating each spindle while in such operating position, a frame, a pair of shafts mounted in said frame, each of said shafts being provided with sanding 40 brushes, the brushes on each shaft being arranged to operate upon work carried by one of said work spindles, means for oscillating said shafts so as to cause the respective 45 brushes successively to contact with the work carried by the respective work spindles when in operative position, and means for locking the work spindles against oscillation during desired intervals.

3. In a sanding machine in combination with a shaft, work spindles mounted on said shaft and carried on opposite sides thereof, means for oscillating said shaft so as to bring 55 said work spindles alternately in an operative position and means for rotating each spindle while in such operating position, a frame, a pair of shafts mounted in said frame, each of said shafts being provided with sanding 60 brushes, the brushes on each shaft being arranged to operate upon work carried by one of said work spindles, means for oscillating said shafts so as to cause the respective 65 brushes successively to contact with the work carried by the respective work spindles when in operative position, and means for locking the work spin-

dles when in operative position, and means for oscillating the sanding brushes longitudinally of the spindle during operation.

4. In a sanding machine in combination with a shaft, work spindles mounted on said shaft and carried on opposite sides thereof, means for oscillating said shaft so as to bring 70 said work spindles alternately in an operative position and means for rotating each spindle while in such operating position, a frame, a pair of shafts mounted in said frame, each of said shafts being provided with sanding brushes, the brushes on each shaft being arranged to operate upon work carried by one 75 of said work spindles, means for oscillating said shafts so as to cause the respective brushes successively to contact with the work carried by the respective work spindles when in operative position, means for locking the work spindles against oscillation during 80 desired intervals and means for oscillating the sanding brushes longitudinally of the spindle during operation.

5. In a sanding machine in combination, a shaft, work spindles mounted on said shaft and carried on opposite sides thereof, means for oscillating said shaft so as to bring 85 said work spindles alternately in an operative position, a pulley for the operation of each of said work spindles, a continuous belt arranged to contact and drive each of said pulleys when the spindle is in operative position, an idler pulley mounted on said shaft and arranged to carry said belt during the oscillation of said shaft, a frame, a pair of shafts 90 mounted in said frame, each of said shafts being provided with sanding brushes, the brushes on each shaft being arranged to operate upon work carried by one of said work spindles, and means for oscillating said shafts 95 so as to cause the respective brushes successively to contact with the work carried by the respective work spindles when in operative position.

6. In a sanding machine in combination, a shaft, work spindles mounted on said shaft and carried on opposite sides thereof, means for oscillating said shaft so as to bring 100 said work spindles alternately in an operative position, a pulley for the operation of each of said work spindles, a continuous belt arranged to contact and drive each of said pulleys when the spindle is in operative position, an idler pulley mounted on said shaft and arranged to carry said belt during the oscillation of said shaft, a frame, a pair of shafts 105 mounted in said frame, each of said shafts being provided with sanding brushes, the brushes on each shaft being arranged to operate upon work carried by one of said work spindles, and means for oscillating said shafts so as to cause the respective brushes successively to contact with the work carried by the respective work spindles when in operative position.

7. In a sanding machine in combination, a shaft, work spindles mounted on said shaft and carried on opposite sides thereof, means for oscillating said shaft so as to bring 110 said work spindles alternately in an operative position, a pulley for the operation of each of said work spindles, a continuous belt arranged to contact and drive each of said pulleys when the spindle is in operative position, an idler pulley mounted on said shaft and arranged to carry said belt during the oscillation of said shaft, a frame, a pair of shafts 115 mounted in said frame, each of said shafts being provided with sanding brushes, the brushes on each shaft being arranged to operate upon work carried by one of said work spindles, and means for oscillating said shafts so as to cause the respective brushes successively to contact with the work carried by the respective work spindles when in operative position, and means for locking the work spindles against oscillation during desired intervals.

dles against oscillation during desired intervals.

7. In a sanding machine in combination, a shaft, work spindles mounted on said shaft and carried on opposite sides thereof, means for oscillating said shaft so as to bring said work spindles alternately in an operative position, a pulley for the operation of each of said work spindles, a continuous belt arranged to contact and drive each of said pulleys when the spindle is in operative position, an idler pulley mounted on said shaft and arranged to carry said belt during the oscillation of said shaft, a frame, a pair of shafts mounted in said frame, each of said shafts being provided with sanding brushes, the brushes on each shaft being arranged to operate upon work carried by one of said work spindles, means for oscillating said shafts so as to cause the respective brushes successively to contact with the work carried by the respective work spindles when in operative position, and means for oscillating the sanding brushes longitudinally of the spindle during operation.

8. In a sanding machine in combination, a shaft, work spindles mounted on said shaft and carried on opposite sides thereof, means for oscillating said shaft so as to bring said work spindles alternately in an operative position, a pulley for the operation of each of said work spindles, a continuous belt arranged to contact and drive each of said pulleys when the spindle is in operative position, an idler pulley mounted on said shaft and arranged to carry said belt during the oscillation of said shaft, a frame, a pair of shafts mounted in said frame, each of said shafts being provided with sanding brushes, the brushes on each shaft being arranged to operate upon work carried by one of said work spindles, means for oscillating said shafts so as to cause the respective brushes successively to contact with the work carried by the respective work spindles when in operative position, means for locking the work spindles against oscillation during desired intervals, and means for oscillating the sanding brushes longitudinally of the spindle during operation.

9. In a sanding machine in combination with pivotally suspended sanding brushes, a shaft, work spindles mounted on said shaft and carried on opposite sides thereof, means for oscillating said shaft so as to bring said work spindles alternately in operative position, means for rotating each spindle while in such operative position, and means for oscillating said brushes on their pivotal mountings longitudinally of the respective work spindles.

GEORGE A. SCHIPPER.
